UNITED STATES PATENT OFFICE.

ALEKSANDER PLUDOWSKI AND STANISLAW ORLOWSKI, OF WATERBURY, CONNECTICUT, ASSIGNORS OF ONE-HALF TO WLADYSLAW SZCZEPANIAK, OF WATERBURY, CONNECTICUT.

DESIGN FOR A TONGUED MILK-BOTTLE CAP.

49,751.

Specification for Design.

Patented Oct. 10, 1916.

Application filed June 23, 1916. Serial No. 105,522. Term of patent 7 years.

To all whom it may concern:

Be it known that we, ALEKSANDER PLUDOWSKI and STANISLAW ORLOWSKI, subjects of the Czar of Russia, residing at Waterbury, in the county of New Haven and State of Connecticut, have invented a new, original, and ornamental Design for Tongued Milk-Bottle Caps, of which the following is a specification, reference being had to the accompanying drawings, forming part thereof.

The figure is a view in perspective of a milk bottle cap, showing our new design.

We claim:

The ornamental design for a tongued milk bottle cap, as shown.

ALEKSANDER PLUDOWSKI.
STANISLAW ORLOWSKI.

Witnesses:

JOHN T. STERLING,
WLADYSLAW RODZIEWICZ.
